CARTRIDGE HOLDER AND DISPENSER

John W. Kirby, Memphis, Tenn.

Application January 17, 1947, Serial No. 722,631

7 Claims. (Cl. 224—15)

1

This invention relates to cartridge holders for the use as of hunters and other marksmen, and particularly to a holder which is adapted to receive the content of a box of cartridges as a group, and will hold the cartridges so inserted for dispensing, and which may be manually operated to successively dispense the transverse rows, usually of five cartridges each, as they were packed in the original box. It further relates to such a cartridge holder which may be conveniently supported as by a belt around the waist of the user.

Cartridges for rifles and small arms are usually packed and sold to the users, in boxes holding fifty cartridges disposed in ten transverse rows of five each, and many rifles and most small arms have magazines or chambers holding five, six, ten, or more cartridges which may at option be filled or partially filled at one time with one or more dispensings.

The objects of the present invention are:

To provide a cartridge holder into which the entire content of the box in which cartridges are purchased may be readily transferred without disturbing the row arrangement of the cartridges as they were assembled in the box.

To provide such a holder which may be manipulated to remove as a group the cartridges of each transverse row in succession.

To provide such a holder which will maintain the row relation of the cartridges, whether the holder be full or have one row only remaining at all times; and

Which will simplify and improve the design and construction of such holders and dispensers.

The means by which the foregoing and other objects are accomplished and the manner of their accomplishment will be readily understood from the following specification upon reference to the accompanying drawings, in which:

Fig. 1 is a sectional elevation of the holder fully loaded, taken on the line I—I of Fig. 2.

Fig. 2 is a transverse sectional elevation taken on the line II—II of Fig. 1.

Fig. 3 is a plan view.

Fig. 4 is an inverted sectional plan taken through the dispensing mechanism on the line IV—IV of Fig. 1.

Fig. 5 is a sectional elevation taken, as was Fig. 1, on the line I—I of Fig. 2, with the closure slide or door raised and a box of cartridges being inserted.

Fig. 6 is an inverted plan view.

Fig. 7 is a fragmentary section taken on the line VII—VII of Fig. 5 showing the slide lock.

2

Referring now to the drawings in which the various parts are indicated by numerals:

The cartridge holder is a relatively elongated rectangular, box-like structure having vertically disposed side walls 12, a back wall 14, and a horizontal top wall 16 integrated together, the side walls preferably having bracing portions 12A extending rearwardly of the back wall 14. At its lower end the back wall 14 has a rearward extension 18 which overlies a plate-like top portion 20 of an ejector, the extension forming a cover portion of a housing for the ejector. The extension 18 is braced by the side wall portions 12A and at its rear edge has a downwardly extending flange 22 forming the back end of the ejector housing. The side walls 12 extend downward to the level of the extension 18 and therebelow have portions 12B, stepped outwardly the thickness of the sides 24 of the ejector, to form the sides of the ejector housing.

The front edges of the sides 12 of the holder have outwardly extending flanges 12C which are forwardly and inwardly curved to form grooves adapted to slidably receive the side edges of a front wall or shutter 28 forming a closure for the front of the holder. At its lower end the shutter has a forward extension 30, which is preferably braced from the shutter by side flanges 32. The extension has a downwardly flanged front edge 34, the extension and flange, when the shutter is seated, forming respectively the top and front end of the ejector housing. Downwardly turned side flanges 36 of the extension form sides completing the forward end of the housing.

The top 16 of the holder preferably has an upwardly extending flange 38 which is engaged by hook portions 40 at the top of the shutter limiting downward movement. One edge of the wall is notched, preferably adjacent the top, for engagement by a latch 42 securing the shutter when in place. 44 is a lifting lug. A belt loop 46 may be secured to one of the side walls 12 for hanging the holder, as from the belt of the user.

The ejector is reciprocably mounted in the ejector housing and includes the top portion 20, of length to be housed in the rear portion of the housing, this top portion having a downwardly extending pusher flange 20A at its forward end and a similarly extending grip 20B cut out of and downwardly bent adjacent its rear end. Portions 24A of the sides 24 of the ejector extend forwardly from the flange 20A to the front wall 28 of the cartridge holder and below the wall are connected by a front portion 24B, forming a car-

tridge receiving pocket, fully open top and bottom. Underlying the ejector and forming the bottom of the ejector housing is a plate 48, extending over at least the rear half of the open bottom of the cartridge holder and of the ejector pocket when the ejector is retracted. The rear portion of the plate (Fig. 6) is cut out to allow protrusion of the ejector grip. Extending upward from the plate is a lug 48A which engages one leg of a compression spring 50, having its opposite leg engaging the ejector grip to hold the ejector retracted. The sides 48B, and the rear end 48C of the plate are turned up against the sides 12B and end 22 of the ejector housing and secured thereto.

A follower 52 is slidably disposed in the cartridge holder, and a compression spring 54 interposed between the top 16 and the follower. The follower is preferably of open top box type having a thin head portion 52A against which the spring bears, and side walls 52B which cooperate with the walls of the holder to guide the follower, and house the spring. The spring preferably is of light weight wire, and its consequent pressure on the follower is sufficient only to hold the cartridges against displacement in the holder, allowing dispensing largely to be effected by the weight of the cartridges.

It will be understood that the holders must be of size to accommodate the particular ammunition and the box in which it is purchased, except that a holder, having fore and aft depth for long cartridges, may also be used for shorter cartridges.

In use, the latch 42 is displaced, releasing the shutter 28 and the shutter lifted by the lug 44 sufficiently to provide for insertion of the cartridge box, or if desired, the shutter is entirely removed. The cover is removed from the box in which the cartridges are contained, leaving the cartridges 56 as originally packed in the lower half of the box 58. The follower 52 is raised against the pressure of the spring 54 and the box with the cartridges packed therein is inserted in the holder with the open top of the box facing inward, until the cartridges seat against the back 14 and the follower is released against the box. The holder is then tipped until the back 14 becomes the bottom and the box is withdrawn, leaving the cartridges in the holder and the follower pressing against them. The shutter 28 is replaced and latched.

Removal of the cartridge box allows the follower to press the cartridges toward the ejector, and the lower row of cartridges into the ejector and against the plate 48 forming the bottom of the ejector housing. To eject cartridges from the holder the grip 20B is engaged by the operator's finger and the ejector shifted forward until the lower row of cartridges is displaced from the plate 48 and drop from the holder. As this displacement takes place the top 20 of the ejector is shifted into place below the next row of cartridges, holding them until release of the ejector grip allows the spring 50 to shift the ejector into position to receive the next lower row, and the row to drop into the ejector pocket.

It will be understood that many of the details herein are illustrative only and that it is not my intention to confine myself to such detail except as in any claim it is specifically set out.

It will be also specifically understood that the bottom 48 may underlie the entire open bottom of the holder and the side wall portions 24A and

forward end of the ejector 24B may be eliminated without departing from my invention.

I claim:

1. A cartridge holder and ejector, including an elongated rectangular box-like structure, having upright back and side walls and an upper end rigidly secured together, and a removable front wall, and means for latching said front wall in closed relation to said side walls and end, the lower end of said holder being open, a follower within said holder slidably along said walls and a compression spring interposed between said upper end and said follower; a relatively shallow ejector housing disposed transversely across and below the open lower end of said holder, said housing having top wall portions respectively extending forward and rearward from the lower end of the front and back of said holder, side walls having their inner surfaces continuing the outer surface of the side walls of said holder and extending forwardly and rearwardly therefrom; and a bottom spaced at its forward end not more than half the fore and aft depth of said holder rearwardly from said front wall and extending rearwardly beyond said back wall; a manually operable ejector, slidably disposed in said housing, said ejector having a front member, side members and a transverse member underlying the walls of said holder, said members outlining a pocket which is open top and bottom, said pocket conforming to the cross section of said holder and being adapted in retracted position of said ejector to underlie said holder, said ejector having a plate-like top portion extending rearwardly from the top of said transverse member, and a spring cooperating with said ejector and said housing to urge said ejector into retracted position.
2. A cartridge holder and ejector in conformity with claim 1, in which the top wall portion of said housing is respectively secured to and braced from said front and back walls.
3. A cartridge holder and ejector, including an elongated rectangular box-like structure, having upright back and side walls and an upper end rigidly secured together, and a removable front wall, and means for latching said front wall in closed relation to said side walls and end, the lower end of said holder being open; a follower within said holder slidably along said walls and a compression spring interposed between said upper end and said follower; a relatively shallow ejector housing secured transversely across and below the open lower end of said holder, said housing having a top wall apertured to conform to the open lower end of said holder, side walls substantially co-extensive with said top wall, and a bottom spaced at its forward end not more than half the fore and aft depth of said holder rearwardly from said front wall and extending rearwardly beyond said back wall; a manually operable ejector, slidably disposed in said housing, said ejector having a front member, side members and a transverse member, said members outlining a pocket which is open top and bottom, said pocket conforming to the cross section of said holder and being adapted in retracted position of said ejector to underlie said holder, said ejector having a plate-like top portion extending rearwardly from the top of said transverse member, and a spring cooperating with said ejector and said housing to urge said ejector into retracted position.
4. A cartridge holder and ejector, including an elongated rectangular box-like structure having upright back and side walls, and an upper end

rigidly secured together, and a front wall, the front edges of said side walls being grooved to slidably receive said front wall, and means for latching said front wall in closed relation to said side walls, the lower end of said holder being open; a follower within said holder slidable along said walls and a compression spring interposed between said upper end and said follower; a relatively shallow ejector housing secured below the open lower end of said holder, said housing having a top extending fore and aft of said holder and apertured to conform to the open lower end of said holder, side walls substantially co-extensive with said top wall, and a bottom spaced at its forward end substantially half the fore and aft depth of said holder rearwardly from said front wall and extending rearwardly beyond said back wall; a manually operable ejector, slidably disposed in said housing, said ejector having front and rear transverse members, and side members, said members outlining a pocket which is open top and bottom, said pocket conforming to the cross section of said holder and being adapted in retracted position of said ejector to underlie said holder, said ejector having a plate-like top portion extending rearwardly from the top of said rear transverse member, and a spring cooperating with said ejector and said housing to urge said ejector into retracted position.

5. A cartridge holder and ejector, including an elongated rectangular box-like structure, having upright back and side walls and an upper end rigidly secured together, and a removable front wall, and means for latching said front wall in closed relation to said side walls and end, the lower end of said holder being open; a follower within said holder slidable along said walls and a compression spring interposed between said upper end and said follower; a relatively shallow ejector housing secured below the open lower end of said holder, said housing having a top extending forwardly and rearwardly from said holder and apertured to conform to the open lower end of said holder, side walls substantially co-extensive with said top, and a bottom portion underlying said holder and extending rearwardly beyond the back wall thereof; a manually operable ejector, slidably disposed in said housing, said ejector having a transverse member adapted in retracted position of said ejector to underlie said holder, and having a plate-like top portion extending rearwardly from the top of said transverse member; and a spring cooperating with said ejector and said housing to urge said ejector into retracted position.

6. A cartridge holder and ejector, including an elongated rectangular box-like structure, having upright back and side walls and an upper end rigidly secured together, and a removable front wall, and means for latching said front wall in closed relation to said side walls and end, the lower end of said holder being open; a follower

within said holder slidable along said walls and a compression spring interposed between said upper end and said follower; a relatively shallow ejector housing secured below the open lower end of said holder, said housing having a top extending fore and aft of said holder and apertured to conform to the open lower end of said holder, side walls substantially co-extensive with said top, and a bottom portion underlying said holder and extending rearwardly beyond said back wall; a manually operable ejector, slidably disposed in said housing, said ejector having a front member, side members and a transverse member, said members outlining a pocket which is open top and bottom, said pocket conforming to the cross section of said holder and being adapted in retracted position of said ejector to underlie said holder, said ejector having a plate-like top portion extending rearwardly from the top of said transverse member; and a spring cooperating with said ejector and said housing to urge said ejector into retracted position.

7. A cartridge holder and ejector, including an elongated rectangular box-like structure, having upright back and side walls and an upper end rigidly secured together, and a removable front wall, and means for latching said front wall in closed relation to said side walls and end, the lower end of said holder being open; a follower within said holder slidable along said walls and a compression spring interposed between said upper end and said follower; a relatively shallow ejector housing secured below the open lower end of said holder, said housing having a top extending fore and aft of said holder and apertured to conform to the open lower end of said holder, side walls substantially co-extensive with said top, and a bottom spaced at its forward end not more than half the fore and aft depth of said holder rearwardly from said front wall, and extending rearwardly beyond said back wall; a manually operable ejector, slidably disposed in said housing, said ejector having a transverse member adapted in retracted position of said ejector to underlie the rear wall of said holder, and having a plate-like top portion extending rearwardly from the top of said transverse member; and a spring cooperating with said ejector and said housing to urge said ejector into retracted position.
